UNITED STATES PATENT OFFICE.

WILLIAM R. WARNER, OF PHILADELPHIA, PENNSYLVANIA.

DESIGN FOR GLASS VESSELS.

SPECIFICATION forming part of Design No. 11,667, dated March 2, 1880.

Application filed February 6, 1880. Term of patent 14 years.

To all whom it may concern:

Be it known that I, WILLIAM R. WARNER, of Philadelphia, Pennsylvania, and a citizen of the United States, have invented and produced a new and original Design for Glass Vessels, of which the following is a specification.

My design is fully shown in the accompanying drawings, in which—

10 Figure 1 represents a perspective view of the vessel, and Fig. 2 a side view of the same.

The body A of the vessel is of spherical form, slightly flattened at the top, and is connected to a slightly conical base, B, by a central 15 stem, D.

The spherical body A has a central circumferential rib or flange, a, of tapering form, and the stem D is enlarged at or about the center, so as to form a semicircular rib, b.

20 I do not desire to claim, broadly, a design comprising a spherical body, circular or conical base, and vertical connecting-stem; but

I claim—

1. The design for a glass vessel, said design comprising a base, B, a connecting-stem, D, 25 and a spherical body, A, having a central circumferential rib, a, all substantially as described and shown.

2. The design for a glass vessel, said design comprising a spherical body, A, a base, B, 30 and a connecting-stem, D, with rib b, as described and shown.

3. The design for a glass vessel, said design comprising the spherical body A, with central circumferential rib, a, the base B, and the connecting-stem D, having a rib, b, as described 35 and shown.

In testimony whereof I have signed my name to this specification in the presence of two subscribing witnesses.

WILLIAM R. WARNER.
